UNITED STATES PATENT OFFICE.

CHARLES R. HERRICK AND DANIEL W. BILLINGS, OF FENWICK, MICH.

LIFE-BOAT.

SPECIFICATION forming part of Letters Patent No. 349,499, dated September 21, 1886.

Application filed December 3, 1885. Serial No. 184,544. (No model.)

To all whom it may concern:

Be it known that we, CHARLES R. HERRICK and DANIEL W. BILLINGS, citizens of the United States, residing at Fenwick, in the county of Montcalm and State of Michigan, have invented certain new and useful Improvements in Life-Boats; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention has relation to improvements in life-boats; and it consists in the construction, novel arrangement, and adaptation of devices, as will be hereinafter more fully set forth, and pointed out in the claims.

20 The object of the invention is to provide a boat which may be cheaply constructed, buoyant, durable, and air-tight, and one that will readily right itself when capsized. These objects we accomplish by the means shown in 25 the accompanying drawings, in which—

Figure 1 is a side view of a boat constructed according to our invention. Fig. 2 is a vertical section in detail through one of the air-ports J and its valve or plunger and handle. 30 Fig. 3 is a horizontal cross-section through the pump, and the check-valve in the discharge-pipe thereof.

In carrying out our invention we form the body of the boat in torpedo shape, being composed of staves and hoops. The staves taper on their longitudinal edges toward opposite ends, and are securely held in position by means of external hoops, as shown. The external hoops are advantageous over internal 35 hoops, as they may be driven on from each end and force the staves into close conjunction, besides obviating the danger of the fastening devices becoming loosened, as might be the case were internal hoops used, it being necessary to break the external hoop before 40 the staves will be loosened or spread. This body may have a wheel-house about midway its length and in the longitudinal central line of the boat, or it may have a wheel-house on 45 opposite sides when it is desirable to use two wheels. When two wheels are employed, a

crank-shaft is carried through the boat transversely, so as to afford the occupants a convenient means of propelling it. We do not, however, wish to confine ourselves to any particular devices for propelling the boat, as it is obvious that various means may be employed without departing from the spirit of our invention.

We provide a suitable keel on the proper longitudinal side, and also a helm having an operating-shaft, which is carried into the boat through a packed aperture to prevent the introduction of water, as is also the bearings of the wheel-shaft. We provide the side diametrically opposite the keel with an annular or oblong platform and a hatchway, which may be surrounded by a suitable guard.

Referring by letter to the said drawings, A indicates the boat-body, which is circular in cross-section and tapers to opposite ends from its central portion. This body may be provided with windows B and a ladder leading from the hatchway G to the inner floor, as more fully shown in dotted lines.

75 C indicates the keel, and D the helm.

E indicates the wheel-house, and F the wheel therein.

H indicates the platform, and I the hatchway. The hatch-door may be provided with 80 rubber or the like in its engaging parts, so as to form an air and water tight joint when closed.

J indicates air-ports arranged on the top of the boat, and one at each end of the platform, and are each constructed with an external flaring air-collector, from which leads into the boat a rectangular pipe having an aperture, a^2 , for the admission of air and water, as shown in Fig. 2. These ports are provided with valves or elastic plungers a' , which enter the said ports, and are connected with pivoted hand-levers $a a$, as clearly shown in Fig. 2, whereby the said ports may be opened and closed, as desired, and the hatch is provided with a sight, so that the occupants may look out from the boat, and when its top is above the surface of the water open its ports for ventilation. The two levers $a a$ are arranged at or near the middle of the length of the boat, and in such close relation to each other that one man can close or open both valves when desired. By this construction the boat may

be made both air and water tight; but should any water enter from the ports or otherwise, it may be drawn out and discharged by the pump K, which is provided with a check-valve 5 in its discharge-spout, as shown in Fig. 3.

This invention is especially designed for life-boats, which in a heavy sea are sometimes nearly or completely submerged. The two ports J J, which supply air to the interior of the boat for sustaining life therein, will frequently take in water, and require to be frequently closed by the plungers or valves a', to do which and to have a "double-ender" 10 the two air-supply ports, their valves, and the two independent levers a a are necessary for the purpose of properly ventilating the interior of the boat and making it practically operative. In combination with the said air-supply ports and their valves and independent operative parts, and for the purpose of relieving the boat of water taken in through the ports, we must employ a pumping-engine, K, located, substantially as shown in Fig. 1, for the purpose of forcibly discharging this water 15 from the interior of the boat as rapidly as it accumulates.

Having described our invention, what we claim is—

1. A life-boat provided with air-ports J, located near the ends of the staging or deck, 30 and communicating with the interior of the boat by means of angular pipes provided with inlets, in combination with plungers in said pipes for closing said inlets, connected by rods to hand-levers, substantially as described. 35

2. A life-boat consisting of a cigar-shaped hull constructed as described, and provided with wheel-houses, propellers therein, windows, a staging or deck, a broad keel, a pilot-house having windows, air-collectors at both 40 ends of the staging, valves therein operative as described, and a pumping-out engine, as shown and described.

In testimony whereof we affix our signatures in presence of two witnesses.

CHARLES R. HERRICK.
DANIEL W. BILLINGS.
